(57) **CLAIM**

The ornamental design for a bottle with trigger spray, as shown and described.

DESCRIPTION

FIG. 1 is a front perspective top view of a new design of a bottle with trigger spray;

FIG. 2 is a front side elevational view thereof;

FIG. 3 is a back side elevational view thereof;

FIG. 4 is a side elevational view thereof;

FIG. 5 is another side elevational view thereof;

FIG. 6 is a top plan view thereof; and,

FIG. 7 is a bottom perspective view thereof.

The broken lines in the drawings and the areas within depict portions of the bottle with trigger spray that form no part of the claimed design.

1 Claim, 5 Drawing Sheets
